INVENTOR,
Ernest J. Wheeler,

BY

Harry W. Brown.

ATTORNEY.

UNITED STATES PATENT OFFICE.

ERNEST J. WHEELER, OF SPRINGFIELD, MASSACHUSETTS, ASSIGNOR TO THE UNITED STATES SPRING BED COMPANY, OF SPRINGFIELD, MASSACHUSETTS, A CORPORATION OF MASSACHUSETTS.

FOLDING COT.

1,265,848.

Specification of Letters Patent. Patented May 14, 1918.

Application filed November 9, 1917. Serial No. 201,037.

To all whom it may concern:

Be it known that I, ERNEST J. WHEELER, a citizen of the United States of America, residing at Springfield, in the county of 5 Hampden and State of Massachusetts, have invented certain new and useful Improvements in Folding Cots, of which the following is a specification.

This invention relates to improvements in 10 folding cots, or couches, and is of the type in which a mattress composed of wire links or woven fabric, is attached to frame work by means of suitable spring, or links. Some 15 of the objects of the invention are to provide a cot, or couch, that can be readily folded into a small compass for the purpose of easily carrying it from one room to another as desired, for extending the ends of the cot to form a bed so that its ends will 20 lie in the same horizontal plane; or, to permit folding up the ends, upward with relation to the central portion of the cot, to form a divan, or, to fold a portion of the cot downward to form a supporting leg for 25 one end of the cot and the other end upward to form the back of a chair, all as will be fully described in the specification and definitely pointed out in the claims.

Referring to the drawings: 30 Figure 1 is a plan view showing the cot extended with a portion of the fabric broken away to illustrate the brace devices which retain the main body or central portion of the cot extended and which also hold the 35 legs in a fixed position.

Fig. 2 is a side elevational view of Fig. 1, the full lines representing the cot extended, the dotted lines showing the manner of folding the end portions of the cot upward toward each other to form a divan, or downward to illustrate the position of the joined 40 parts of the cot when same is to be folded.

Fig. 3 is a side elevational view showing the cot when folded and used as a chair.

Fig. 4 shows the parts of the cot folded into a compact compass.

Fig. 5 is a detail view of the leg brace.

Figs. 6 and 7 are detailed views of the latch devices.

50 Referring to the drawing in detail:

The side portions of the cot are preferably formed of angle iron portions, which portions are indicated by the numerals 1, 2, 3, 4, 5, 6, 7 and 8. The end portions of the

cot are also formed of angle irons that are 55 indicated at 9 and 10, and which are secured to the side pieces 1, 4, 5 and 8 by means of rivets 11. The inner ends of the pieces 2, 3, 6 and 7 are pivotally attached to a brace bar 12 by means of the pivot pins 13, 60 14, 15 and 16. Pivotally secured to the outer ends of the side portions 2, 3, 6 and 7 are legs 17 and 18, only two of which are shown, by means of pivots 19 and 20. Connecting the upper ends of the legs 17 and 18 65 are braces 21 and 22 which are clearly shown in the plan view Fig. 1 and are preferably made of tubing. Extending from the centrally located brace bar 12 to the brace bars 21 and 22 are pivotally connected links 23 70 and 24 similar to a toggle-link, which are joined together at their inner ends by means of the pivots 25. A part 26 with hook-shaped portions serves to maintain the links 23 and 24 in their extended position. These 75 links are connected to the rods 21 and 22 by means of the straps 27, which straps have a loose fitting rotatable connection with the rods 21 and 22, so that they may rotate around these rods when the cot is folded as 80 shown in Figs. 2 and 4, and a pivotal connection with links 23 and 24 is indicated at 28. Also the links 24 at their inner ends have a pivotal and rotatable connection with the bar 12 by means of the straps 29 and 85 pivots 30. The end portions or bars of angle irons 1, 4, 5 and 8, of the cot, are pivotally connected to the centrally located side bars 2, 3, 6 and 8 by means of the strap hinges 31, which are pivoted together as 90 indicated at 32. For the purpose of retaining the ends 1, 4, 5 and 8, in elevated position, supporting braces 33 are provided which are pivotally connected to the end bars 1, 4, 5, and 8 of the cot as indicated 95 at 34. These braces are formed with teeth 35 near their lower ends. These braces pass through openings 35' in the web of the angle iron of which the legs are made for the purpose of retaining the braces so that they 100 will engage shoulders of the openings, as shown in Fig. 5. A wire 36 has one end secured to the end bars as indicated at 37, and its other end provided with a spring 105 38, which is also attached to the end bars 1, 4, 5 and 8, as indicated at 38. The wire 36 passes under a pin 33² of the brace 33. The spring 38 is of sufficient stiffness to

cause the links 33 to be rigidly held in any desired position, that is to say, either folded or extended. A cord, or other device 40, extends from a rod 40' connecting the 5 notched braces 33 to the end portions 9 and 10 of the cot. The cord is for the purpose of enabling the operator to unlatch the braces 33 from the legs by pulling outward on the cord 40 in the direction of the arrow 40'.

The usual fabric, or bed bottom, is indicated at 41, and may be composed either of wire links or some woven material, as canvas. This fabric is connected to the side 15 portions of the cot by means of the usual coiled springs 42.

Referring to Fig. 2, it is noticed that the end portions 1, 4, 5 and 8 are folded upward in relation to the centrally located portion 20 of the cot into the dotted line positions 1' and 4', for the purpose of forming a divan, or sofa structure, these ends being supported in this position by means of the notched braces 33.

25 Referring to Fig. 3, in which the structure is shown folded so as to serve as a chair, the ends 4 are turned upward while the ends 1 and 8 are folded on the pivots 32 inward against the sides 2 and 7, which sides 30 serve as the forward legs of the chair and these sides are braced by means of the legs 17, to which a pivotally connected latch 43 is attached. This latch engages a pin 44 on the side pieces 3 and 6.

35 Fig. 4 represents the manner of folding the cot into a small compass for enabling it to be easily carried about. The ends 1, 8, 4 and 5 are folded toward each other so as to engage the top portions of the side pieces 40 2, 3, 6 and 7, while the legs 17 and 18 are folded inward so as to engage the under side of the side pieces 2, 3, 6 and 8. The whole is then held together about the pivots 18 and 14 and secured by means of the latch 45 which engages the pin 45' on the end piece 9. Cross bars 21 and 22 are held in place by means of the latch 45' which engages the pin 45' (see Fig. 1) whereby the cot can be readily carried from one part of the building to another, the dimensions and weight of the cot being such that it may be easily transported by one person.

The arrows in Fig. 2 clearly indicate the manner of folding the cot into position shown in Fig. 4. The pivotally connected links 23 and 24, it will be understood, are moved into the dotted line position indicated in Fig. 1 before the cot is folded. The springs 23' normally maintain the links 23 and 24 extended. The straps 27 and 29 readily permit the links 23 and 24 to turn about the brace rods 12, 21 and 22. Also, the wire 36 and springs 38 readily permit the notched braces 33 to be turned on the pivots 34 and folded into the angle iron por-

tions of the ends 1, 4, 5, and 8 as indicated in Fig. 2.

What I claim is:

1. In a foldable cot, the combination with centrally located and end members that are pivotally connected together, the end members being foldable outward into a plane with the upper surface of the centrally located members, of legs pivotally connected to the ends of the centrally located members, 70 a brace bar directly and pivotally connected to the inner ends of the centrally located members, braces connecting the upper ends of the legs together, foldable braces extending from the braces connecting the upper ends of the legs to the brace connecting the inner ends of the centrally located members, the foldable braces having a hinge connection with said braces whereby the legs and said members may be folded into a small 75 compass, as described.

2. A foldable cot comprising, in combination, members composing the body portion that are pivotally connected together, legs for supporting the members, the pivotally 90 connected ends of the cot serving to form a divan, or sofa, when folded upward toward each other, braces for retaining the ends of the cot in this upward position, said braces comprising pieces having notches at their lower ends for engaging a shoulder portion on the legs, means for retaining the braces in different positions of adjustment 95 comprising friction means secured to the end-members and engaging the braces, and springs secured to the friction means for permitting the braces to be operated, as described.

3. A foldable cot, comprising, in combination, centrally located and end members that are pivotally connected together, the end members being foldable outward into the plane of the centrally located members, legs pivotally connected to the ends of the centrally located members, foldable links 110 connected to the legs and to the centrally located members, devices to permit the foldable links to turn about their connections with the legs and said centrally located members, and devices for retaining the foldable end members of the cot in different positions of adjustment.

4. In a foldable cot, the combination with sections that are pivotally connected, of legs pivotally connected to the cot for supporting the same, pivoted links for retaining the legs in their open position, braces for supporting the end sections and friction devices operable throughout their length for retaining the braces in either their locking or 125 unlocking positions.

5. In a foldable cot, the combination with sections that are pivotally connected, of legs pivotally connected to the cot for supporting the same, links for retaining the legs in 130

- their open position, braces for supporting the end sections and friction devices for retaining the braces in either their locking or unlocking positions on the legs, said friction devices comprising a pin or stud on the brace, a wire attached at one end to the cot, a spring attached to its other end and also to the cot, as described, whereby a tension effect is produced on the stud for holding the brace in different positions.
6. A foldable cot comprising, in combination, centrally located and end sections that are pivotally connected together, legs pivoted to centrally located sections for supporting the cot, a brace as 12 for the sections and legs, toggle joint braces having a swinging and pivotal connection with said braces, the toggle-joint braces serving to maintain the legs in their supporting position and for permitting the sections and legs to move into a folded position, and means comprising a latch on one of the end sections for retaining the sections in closed position.
7. A foldable cot, comprising, in combination, sections pivoted together, a portion of the middle or centrally located section

serving as a supporting leg when the cot is folded to form a chair and means for supporting the end section and legs when the cot is used for a chair.

30

8. A foldable cot, comprising, in combination, sections of angle-iron pivoted together to permit folding, a bed-bottom fabric attached to the sections, a brace to which the inner ends of the centrally located sections are pivotally connected, legs pivotally connected to the outer ends of the centrally located sections, notched braces pivotally connected to the end sections for retaining the end sections in different positions of adjustment, toggle-joint braces, said braces being connected to the legs and to the brace attached to the inner ends of the centrally located sections to permit the sections and legs to be folded inward, the end sections being folded upon the centrally located sections whereby the cot may be folded together into a compact form and latches for retaining the sections and legs in folded position.
